CLAIM

the ornamental design for a bucket shroud, as shown and described.

DESCRIPTION

FIG. 1 is a front perspective view of a bucket shroud showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate structure or features which form no part of the claimed design.

The drawings include surface shading which represents contour and not surface ornamentation.

1 Claim, 6 Drawing Sheets# US D882,646 S
